DESIGN FOR A DRESS

Phyllis Byrnes, New York, N. Y.

Application February 20, 1939, Serial No. 83,099

Term of patent 3½ years

To all whom it may concern:

Be it known that I, Phyllis Byrnes, a citizen of the United States, residing in New York city, in the county of New York and State of New York, have invented a new, original, and ornamental Design for a Dress, of which the following is a specification, reference being had to the accompanying drawing, forming part thereof.

Fig. 1 is the front view of a dress showing my design.

Fig. 2 is the rear view thereof, and,

Fig. 3 is an enlarged fragmentary view of the

dress shown in Fig. 1 illustrating a portion of one of the ribbon trimmed, embroidered bands.

The characteristic feature of my design resides in the combination on the specific dress of the specific bands of eyelet embroidery with interlaced ribbons arranged on the waist and skirt as shown, said ribbons matching the bows on the neckline and on the sleeves.

I claim:

The ornamental design for a dress, substantially as shown and described.

PHYLIS BYRNES.
